Inventor

C. B. Andrews,

By Jack Richmond

Attorney

Patented Apr. 12, 1927.

UNITED STATES PATENT OFFICE.

CHARLES B. ANDREWS, OF HIGH BRIDGE, NEW JERSEY, ASSIGNOR TO TAYLOR-WHARTON IRON AND STEEL COMPANY, OF HIGH BRIDGE, NEW JERSEY, A CORPORATION OF NEW JERSEY.

INNER DISK FOR DISK CRUSHERS.

Application filed June 5, 1925. Serial No. 35,169.

This invention relates to crushing machines of the disk action type, and more particularly to the construction and arrangement of the inner disk.

Inner disks have heretofore been constructed of two or more concentric parts. This practice is adhered to for various reasons, but mainly to provide a certain amount of flexibility in order to relieve the strain on the anchoring element.

The principal objects of my invention are to provide an integral disk construction in which will obviate casting difficulties in that it is capable of the necessary expansion and contraction to avoid the setting up of dangerous or otherwise undesirable strains and stresses, and to provide an integral disk construction having the necessary inherent resiliency to reduce the strain on the anchoring means to a minimum.

An embodiment of the invention is illustrated in the annexed drawings, wherein—

Fig. 1 is a view of the outer face of the inner disk of my invention;

Fig. 2 is a section thereof; and

Fig. 3 is a face view of a modification.

In the drawings, the numeral 5 represents an inner disk of solid or integral construction in accordance with my invention.

It is of general dish shape, as usual, to provide a grinding face 6 and an outer face 7 for co-operation with the usual disk head, not shown. The face 7 has grooves 8, as usual, for the reception of spelter or other filling introduced between the face and the disk head.

In further accordance with my invention I form the disk with an integral flat central anchoring portion 9 having a central bore

or aperture 10 whose walls are tapered to 40 accommodate the head of the usual anchoring bolt shown in dotted lines in Fig. 2. In order to relieve the strain on the anchoring element, the flat portion 9 is afforded the necessary resiliency through the medium of 45 alternate thick and thin sections established by the provision of radial depressed panels or pockets 11, Figs. 1 and 2. The same result may be attained by substituting, for the panels, the slots 12, Fig. 3, thus providing 50 resilient tongues 13 for engagement with the anchoring element.

The inner disk of my invention is preferably constructed of commercial or high 55 per cent manganese steel, the integral construction readily lending itself to the special heat treatment essential to that steel.

Having described my invention, I claim:

1. An inner disk for crushing machines of the disk action type having a centrally 60 apertured integral flat center with panels ranging radially thereof to provide alternate thick and thin metal sections whereby sufficient resiliency is established to relieve the strain on the anchoring means. 65

2. An inner disk for crushing machines of the disk action type consisting of a unitary casting of manganese steel dished to provide a central flat portion and an offset grinding portion, the flat portion having an 70 axial opening to receive an anchoring element, and being radially relieved of metal in the region of said opening whereby it is capable of absorbing flow or stretching of 75 metal in service and so minimize strain on the anchoring element.

In testimony whereof I affix my signature.
CHARLES B. ANDREWS.
